[57] ABSTRACT

A torch lighter box has a pair of spaced switch contacts extending through one face thereof upon which the nozzle of a torch may be placed; also has a pair of spaced ignition contacts extending through the same face aligned with the nozzle, and adapted to form a spark gap for igniting the gas issuing from the nozzle. A battery and a high voltage induction coil are housed within the box. A normally "open" electric circuit within the box connects the pairs of contacts, the battery and the coil, whereby whenever the nozzle is placed across the grounding contacts with gas issuing therefrom a spark will be induced across the ignition contacts to ignite the gas, the nozzle serving as a closing switch for the circuit.

FIG. 2

GAS AND ACETYLENE TORCH LIGHTER

DESCRIPTION OF THE INVENTION

This invention is a novel gas and acetylene torch lighter, comprising a box which is separate from the acetylene torch per se, and which box is provided with spaced closing contacts across which the metallic nozzle of the torch may be placed so as to close the circuit between a battery and high voltage coil in said box and thereby induce a spark across the spaced ignition contacts on the box to ignite the gas issuing from the torch nozzle, the mere placing of the torch on the closing contacts acting as a switch.

Another object of the invention is to provide a gas and acetylene torch lighter of the above type comprising a metallic box, of small dimensions, which has on one face thereof a pair of spaced closing contacts across which the metallic nozzle of the torch may be placed; said closing contacts being insulated from the box itself. Said box also has on the same face thereof, but spaced from the closing contacts, a pair of spaced ignition contacts, also insulated from the box, adapted to form a spark gap for igniting the gas issuing from the nozzle of the torch; said ignition contacts being preferably aligned with the axis of the nozzle when the latter is in closing position.

The box also contains therein a battery, and a high voltage induction coil, and wiring connections between the pairs of contacts, battery, and induction coil to accomplish the desired result, that is, of igniting the gas issuing from the torch nozzle whenever the nozzle is placed across the closing contacts and when gas is issuing from the nozzle, the nozzle, per se, thus serving as a switch for closing the circuit between the pairs of contacts, the battery, and the induction coil.

I will explain the invention with respect to the accompanying drawings, which form a part of this application, in order that others familiar with the art may adopt and use the same; and will summarize in the claims, the novel features of construction, and novel combinations of parts, for which protection is desired.

IN SAID DRAWINGS

FIG. 1 is a perspective view of my novel gas and acetylene torch lighter showing the pairs of spaced contacts, and showing the nozzle of a torch coupling the closing contacts of the box, and setting up a spark across the ignition contacts, and thus igniting the gas issuing from the nozzle.

FIG. 2 is a perspective view of the box, with cover removed, showing the arrangement of the pairs of contacts, the battery, the high voltage induction coil within the box, and showing the wiring circuit connections between the said parts.

As shown in the drawings, my novel gas and acetylene torch lighter comprises a box 1 of small dimensions, preferably rectangular, and preferably formed of metal although same may be formed on any other desired material.

Extending through relatively large bores in one face 1a of the box are a pair of metallic closing contacts 2, 3, which are insulated from the metal of the box, said contacts being spaced apart and disposed horizontally as shown in the drawings, upon which contacts 2, 3, the metallic nozzle N of a gas or acetylene torch T may be placed, the nozzle N acting as a switch to close the elec-

tric circuit contained in the box 1, herein after explained. The inner end of each contact rod 2, 3, is threaded to receive an outside nut 4 in contact with a washer 5 of insulating material which contacts the outer face of box 1a; also a washer 6 of insulating material, similar to washer 5, which engages the inner face of box 1a and is backed up by a locking nut 7, as shown.

Also extending through relatively large bores in the same face 1a of the box are a pair of spaced ignition rod contacts 8, 9, which are preferably vertically disposed and in alignment with and spaced from the tip of the nozzle N, so as to ignite the gases issuing from the nozzle N when a spark is induced across the contacts 8, 9, as shown in FIG. 1. The ignition contacts 8, 9, are insulated from the metal of face 1a of the box in the same manner as above described with respect to closing contacts 2, 3.

Within the box 1 is a battery 10, preferably a 6-volt dry cell battery, the positive terminal of which is connected by wire 11 (FIG. 2) to the closing contact 3, while the negative terminal is connected by wire 12 to the ignition contact 9. Also, within box 1 is a high voltage induction coil 13 (FIG. 2), one terminal of which is connected by wire 14 to the same ignition contact 9 as the wire 12 of the negative terminal of battery 10. Another terminal of coil 13 is connected by wire 15 to the closing contact 2, as shown in FIG. 2; while the third terminal of coil 13 is connected by wire 16 to ignition contact 8 of the box 1, to complete the normally open wiring circuit of the box 1.

Thus, when the metallic nozzle N is placed across the closing contacts 2, 3, as shown in FIG. 1, the wiring circuit of the box 1 will be closed, inducing a spark S across the ignition contacts 8, 9, as shown in FIG. 1, and thereby igniting the gas issuing from the nozzle N, as shown, whereupon the nozzle may be removed from contacts 2, 3, and the lighted torch T used for any desired purpose, separated from the box 1. Upon such removal the circuit within box 1 will assume its normal "open" condition, the nozzle N serving as a switch to close the circuit, as above described.

I claim:

1. A gas and acetylene torch lighter, comprising a metal box; a pair of switch contacts extending through one face of the box and spaced apart to receive and support the nozzle of a torch when placed with the axis of the nozzle extending in a certain direction; a pair of ignition contacts extending through said face and closely spaced from a spark gap, their gap being substantially aligned with said axis of the nozzle for igniting gas issuing from the nozzle; said box containing an electric battery and a high voltage induction coil, and including a normally "open" electric circuit means connecting the battery via the switch contacts to energize the coil whenever a torch nozzle is placed across the switch contacts and including other circuit means coupling the coil to the ignition contacts to induce a spark across the ignition contacts to ignite said gas, said nozzle serving as a closing switch for said circuit said pairs of contacts being electrically insulated from the box.

2. In a lighter as set forth in claim 1, each contact being formed of a metal rod and extending through relatively large holes in the box face, the inner end of each contact rod being threaded; washers of insulating material on said threaded portion of the contacts engaging opposite faces of said box face; and locking nuts on said threaded portion confining said washers respectively.
